Primary Examiner — Mitchell I. Siegel*(74) Attorney, Agent, or Firm* — Randy K. Chang(57) CLAIM

The ornamental design for golf club head, as shown and described.

DESCRIPTION

FIG. 1 is a perspective back view of my new design for a golf club head.

FIG. 2 is a back view thereof;

FIG. 3 is a top view thereof;

FIG. 4 is a bottom sole view thereof;

FIG. 5 is a front view thereof;

FIG. 6 is a heel view thereof; and,

FIG. 7 is a toe view thereof.

The broken lines showing of the golf club head are for illustrative purposes only and forms no part of the claimed design. The vertical lines inside the circular regions on the rear surface of the back of the golf club head indicate the color red.
